UNITED STATES PATENT OFFICE.

JEAN A. JACOBS, OF LONDON, ENGLAND.

LETTER-BOX.

SPECIFICATION forming part of Letters Patent No. 397,552, dated February 12, 1889.

Application filed November 8, 1887. Serial No. 254,656. (No model.)

To all whom it may concern:

Be it known that I, JEAN AUGUST JACOBS, a subject of the Queen of England, and a resident of Seymour Street, Euston Square, 5 London, N. W., in England, have invented a new and useful Improvement in Postal Boxes and the Like, of which the following is a specification.

This invention relates, principally, to boxes 10 or receptacles for the reception of postal-letters and the like, and in general to such boxes or receptacles as are provided with a slit or opening through which articles or things may be passed into said boxes or receptacles, the 15 latter being intended for the safe keeping of said articles or things.

The principal object of the invention is to prevent the extraction of letters or other articles from such postal boxes or other receptacles aforesaid through the slit or opening thereof, through which said letters or articles have been passed into the box or receptacles.

It is known that in the case of ordinary letter-boxes, letters, &c., may be abstracted therefrom through the slit or opening through which they have been passed by means of a string, wire, tape, or the like, carrying a small weight with some adhesive substance thereon, said weight being lowered through said slit 25 onto the letters and drawn up with such letters, &c., as may adhere thereto.

A minor purpose of the invention is to detect if a similar device to that above described has been attempted to be used by preventing 30 the withdrawal of the tape or weight from the letter-box or other receptacle.

The following is a description of the invention in relation to a letter-box capable of being fixed to doors or the like, substantially as 35 ordinary letter-boxes.

Referring to the accompanying drawings, Figure 1 represents a vertical cross-section of the improved letter-box. Fig. 2 is a similar section, on an enlarged scale, of the slit and 45 parts relating thereto, showing the same open. Fig. 3 is a side elevation showing details of the mechanism hereinafter described, such mechanism being in the position occupied when the slit-flap is closed. Fig. 4 is a similar view of the same mechanism in the position 50 occupied when the slit-flap is open. Fig.

5 is a side view of said mechanism as shown in Fig. 3, these three views being on the same scale as Fig. 2.

A represents in cross-section a door, if the 55 box be such, as is attached to a door, or the fore plate of the box.

L is the face-plate surrounding the slit O.

B is the flap covering the slit O, the latter being pivoted at a to lugs or wings on the 60 face-plate L, hereinafter described.

The plate L carries, fixed to or formed with it, three or more plates or wings, b c d, Fig. 2. The upper, or inner plate, b, is substantially flush with the edge of the slot O, and the 65 wings d b c run parallel lengthwise of the lower edge of the slot and are bent perpendicularly round parallel to the sides of the slot, terminating round about the pins a, to form the bearings of said pins. The lower 70 or horizontal parts of the wings d b c are formed as parts of cylinders, the axes of which are coincident with that of the pins a.

The flap B consists of a plate, e, forming the flap proper, said plate adapted to lie 75 when the flap is closed before the slit O, as shown in Fig. 1, and close the same. With the lower edge of said flap is fixed or formed the plate f, extending rearward and continued at the sides of the flap to form wings terminating round about the pins a, and serving for the pivoting of the flap to the plate L—

that is to say, to the wings b c d thereof, as aforesaid. Parallel to the wings f are the wings g and h, the same being continued upward parallel to the side extensions of said wings and terminating likewise about the pins a.

The wings g h are connected to each other and to the wing f by the web j and side webs, k. The horizontal parts of the wings 90 f g h are so shaped as to be parts of cylinders, the axes of which are coincident with that of the pins a, and the wings f g h are so distanced from said pins that when the flap is closed the wings g h arrive and pass into the 95 spaces K' I', between the flaps b c d, and the flaps c d arrive and pass into the spaces K I, between the wings f g h.

The upper edge of the front plate, e, before mentioned, is continued up circularly about the axis of the 100 pivots a over the latter to a distance somewhat farther than a quadrant of a circle, Fig.

2, and above the said edge, so as to be clear from the path thereof, is a downwardly-projecting rim or flange, O', attached or formed on the plate L. As near to the hinge of the 5 flap B as it may conveniently be placed, according to the thickness of the door, &c., A', is pivoted the arm F, having the slot G therein, and the flap B is provided with the pin H, gearing into said slot G. The pin H is extensible 10 to or from the pivots a, and may for this purpose be supported by a screw-threaded pin or pins, J, attached to the rear web, j, passing through perforations in a plate carrying said pin H, there being nuts l on each side of said 15 plate screwing on the pin or pins J, so that the pin-plate H may be fixed at any position along the pins J. The raising and lowering of the flap B about its pivots a therefore raises and lowers, respectively, the arm F about its 20 pivot, and this arm operates the mechanism shown in Figs. 3, 4, and 5, for the purpose or purposes hereinafter shown.

E is the wall of the box, (shown in Fig. 1), and F' is the counterpart of the arm F, being 25 connected to said arm by being fixed on the same pivotal pin traversing the wall E.

Fig. 3 shows the arm F' in the position it occupies when the flap B is closed, and Fig. 4 shows the arm F' in the position it occupies 30 when the flap B is open, as in Fig. 2.

The double lever Q' is pivoted at Q. The upper end thereof carries the horn Q³, the inner edge, Q⁴, of which is shaped as the arc of the circle whose center is the pivotal center 35 of the arm F' when the rear side, Q⁵, of the horn lies against the stop-rail U', as in Fig. 4. At the base of the horn Q³ is the recess Q⁶, equal in breadth to the edge F² of the arm F' and bounded by the two noses Q⁷ Q⁸. The 40 lever Q' being in the position shown in Fig. 3, the lower end, F², of the arm F' engages in the recess Q⁶. When the arm F' commences to press against the nose Q⁸, the lever Q' is moved about its pivot Q until the end of the 45 arm F' is enabled to pass the nose Q⁸ and arrive in the curve Q⁴, which will occur as the rear edge, Q⁵, of the horn Q³ arrives against the stop-rail U'. Further upward movement 50 of the lever Q', but will cause the same to be retained in the position given to it. In the lower end of the lever Q' is the slot Q², and in said slot engages the pin R of the lever R', pivoted on the end of the shaft or rod R², 55 passing through the wall E and traversing the box or receptacle at or near to the front wall thereof, Fig. 1. To this rod is connected the flap or plate D, adapted to be raised so as to form a barrier across the box or receptacle, dividing the same into two compartments, E' E².

M and N are guide-plates, the first serving as an abutment for the outer edge of the plate D, the other as a cover for closing the space 65 between the front wall, A, and the rod R². By moving the lever R' from the position shown in Fig. 3 to that shown in Fig. 4 the

plate D is moved from the position shown in full lines in Fig. 1 to that shown in dotted lines. By this means the communication between the upper compartment, E', and the lower compartment, E², is temporarily closed. 70

The movement aforesaid of the lever R' is entirely made by and during the pressure of the arm F' against the nose Q⁸, and the arm 75 F' will have passed out of the recess Q⁶ and onto the curve Q⁴ before the jaws f h g of the flap B are disengaged from those, b c d, of the plate L. The flap D will therefore be closed before the flap B is opened, and while the latter is open the flap D cannot be opened, since it is locked in its position. When, however, the flap B is fully closed, the flap D is fully 80 opened.

Since the flap B is, owing to its construction, comparatively heavy, a counter-weight is combined therewith to balance the weight of the flap B, and this may be conveniently contrived as follows: The arm F' is connected by a rod, P, with one arm of a bell-crank lever, S', the other arm of which is connected by a rod, T, to the weight U, which is preferably guided between rails U' U². Since, also, the arm F' may be moved to the position shown in Fig. 4 when the flap B is fully open, and the 95 arm F' could not in such position act efficiently to lock the horn Q³, the following additional lock mechanism is preferably combined therewith:

The lever R' is provided with the extending nose R³, the under side, R⁴, of which is curved to be as an arc about the center S of the bell-crank lever S' when the lever R' is in the position shown in Fig. 4—that is to say, when the flap D is closed. The bell-crank lever S' 100 carries the nose S², the outer edge, S³, of which is circular about the center S, and is adapted to ride under and so form an abutment for the nose R³ of the lever R'. The under edge, S⁴, of the nose S² is also so shaped that the 105 nose R³ may lie therein, as shown in Fig. 3, when the flap D is open, and might in case of emergency (as, for instance, the breaking of the lever Q') be raised by such nose S², so as to close and lock the flap D. Thus by the 110 time the arm F' has passed beyond the curve Q⁴ the nose S² has already arrived under the nose R³ and the flap D is held locked.

The flap D is preferably provided with a serrated or toothed edge at D'. It may, however, be replaced by two flaps closing together against each and simultaneously operated; or such other means may be employed, provided that the flap or equivalent D is closed when the flap B is open, and, vice versa, is opened when the flap B is closed. 120

In order to place a letter in the improved letter-box, the flap B is pushed back until the nosing e' arrives beyond the inner edge of the plate b and the letter is dropped in. During 125 this movement, however, the flap D is closed and the letter drops upon this flap. When the flap B is dropped and closed, the flap D opens and the letter drops into the lower

space, E². If, now, it be sought to extract such letter through the slit O, and a weight, with adhesive substance, is lowered into the box by a string, tape, or the like through slot 5 O, the weight will at first rest upon the closed flap D, and after closing the flap B will drop into the space E². By closing the flap B the string, however, is held in the jaws formed by the plates b c d f g h, aforesaid, and cannot be 10 withdrawn unless the flap B be opened, when the flap D will close and the weight or letter attaching thereto will arrive against the edge of said flap D and cannot be withdrawn. The weight cannot therefore be extricated and 15 will remain in the receptacle E², detecting the tampering with the letter-box. To prevent the string or the like from being passed over the hinge of the flap B, the flange O' is contrived, as shown, upon the plate L or otherwise, to form a corner into which the end of the string would pass if pushed up, as described, said corner thus preventing the string from passing over the flap B. The sides of the flap are protected by the jaw-like closing 20 25 of the aforesaid plates b c d f g h extending up the sides of the flap and slit.

What I claim is—

1. In receptacles for postal-letters and other objects, the combination of an upper chamber, E', a lower chamber, E², a flap, D, between said chambers, an orifice, O, opening into the upper chamber, a wing, b, substantially as set forth, beneath said orifice, a pivoted flap, B, adapted to close said orifice, and 30 mechanism connecting said flaps B and D, whereby the initial stage of the opening of the flap B causes the complete closing and locking of the flap D before the flap B has passed the edge of the wing b.

2. In a receptacle consisting of two superposed parts, E' E², the combination of a flap, 40

D, adapted to separate said parts, an orifice, O, in the upper part, E, plates b c d about said orifice, as set forth, flap B, adapted to close said orifice, said flap having plates f g 45 h, adapted to engage with plates b c d, as set forth, and mechanism adapted to be operated by the lifting of said flap B to raise the flap D into its closed position and there lock the same before the plates f g h are disengaged 50 from plates b c d, for the purpose set forth.

3. The combination, with an orifice closed by a hinged flap, of a flange, O', above said hinge, substantially as and for the purpose set forth.

4. The combination, with the flaps B and D, of mechanism comprising the lever F', adapted to be raised by the opening of the flap B, lever Q', having recess Q⁶, with noses Q⁷ Q⁸ and horn Q⁹, slot Q² in said lever Q', 60 rod R², carrying flap D, lever R', fixed on said rod and having pin R, engaging in slot Q², substantially as set forth.

5. The combination, with the flaps B and D, of lever F', adapted to be raised by the 65 opening of flap B, lever Q', having recess Q⁶, with noses Q⁷ Q⁸ and horn Q⁹, the edge Q⁴ being shaped as described, slot Q² in said lever Q', rod R², carrying flap D, lever R', having pin R, engaging in slot Q² and nose R³, the 70 edge R⁴ being shaped as described, lever S', having nose S² with edges S³ S⁴, shaped as described, rods P and T, and counter-weight U, substantially as and for the purpose set forth.

In testimony whereof I have signed this specification in the presence of two subscribing witnesses.

J. A. JACOBS.
